[57] CLAIM

The ornamental design for a magazine/newspaper rack, as shown and described.

DESCRIPTION

FIG. 1 is a perspective view of a magazine/newspaper rack which illustrates my new design;

FIG. 2 is a front elevational view thereof;

FIG. 3 is a right side elevational view thereof, the left side elevational view being a mirror image thereof;

FIG. 4 is a top plan view thereof;

FIG. 5 is a bottom plan view thereof;

FIG. 6 is a rear elevational view thereof;

FIG. 7 is a front perspective view thereof in the position of use with newspapers and magazines being shown in broken lines for illustrative purposes;

FIG. 8 is a front perspective view of a magazine/news-paper rack which illustrates a first alternative embodiment of my new design;

FIG. 9 is a front elevational view thereof;

FIG. 10 is a top plan view thereof;

FIG. 11 is a bottom plan view thereof; and,

FIG. 12 is a rear elevational view thereof.

The right side elevational view thereof is identical to the view shown in FIG. 3, and the left side elevational view is a mirror image thereof.
